UNITED STATES PATENT OFFICE.

ALEXANDER BARBER, OF ROCKWOOD, ILLINOIS.

DESIGN FOR A COFFIN.

SPECIFICATION forming part of Design No. 34,011, dated January 29, 1901.

Application filed January 7, 1901. Serial No. 42,460. Term of patent 7 years.

To all whom it may concern:

Be it known that I, ALEXANDER BARBER, of the city of Rockwood, Randolph county, State of Illinois, have invented and produced 5 a new and original Design for a Coffin, of which the following is a full, clear, and exact description, reference being had to the accompanying drawings, forming a part hereof.

In the drawings, Figure 1 is a perspective 10 view showing my complete design. Fig. 2 is an end view of the same.

As shown in the drawings, the material or 15 essential feature of my design consists of a rectangular body comprising the lower rectangular portion 1 and the upper and larger rectangular portion 2. Above the portion 2 is a smaller rectangular portion 3, and above this is a body 4, extending beyond the sides of the said portion 3. At one end of the body 4 is a square projection 5, upon which 20 is a square body 6, which projects on all sides beyond the sides of the projection 5 and the under edges of which are rounded, as indicated by 7.

I claim—

The design for a coffin or casket, substantially as herein shown and described.

In testimony whereof I affix my signature in presence of two witnesses.

ALEXANDER BARBER.

Witnesses:

ALFRED A. EICKS,
J. W. RIPPEY.
